(57) **CLAIM**

The ornamental design for a photosensitive drum for process
cartridge for image forming apparatus, as shown and
described.

DESCRIPTION

FIG. 1 is a front view of the photosensitive drum for process
cartridge for image forming apparatus.

FIG. 2 is a top view of the photosensitive drum for process
cartridge for image forming apparatus.

FIG. 3 is a bottom view of the photosensitive drum for
process cartridge for image forming apparatus.

FIG. 4 is an enlarged left view of the photosensitive drum for
process cartridge for image forming apparatus.

FIG. 5 is an enlarged right view of the photosensitive drum for
process cartridge for image forming apparatus.

FIG. 6 is an enlarged perspective view of the left portion of
FIG. 1.

FIG. 7 is an enlarged perspective view of right portion of
FIG. 1.

FIG. 8 is a back view of the photosensitive drum for process
cartridge for image forming apparatus.

FIG. 9 is a left view of the photosensitive drum for process
cartridge for image forming apparatus; and,

FIG. 10 is a right view of the photosensitive drum for
process cartridge for image forming apparatus.

The broken lines show portions of the photosensitive drum
for process cartridge for image forming apparatus that form
no part of the claimed design.

1 Claim, 10 Drawing Sheets
